Primary Examiner — Omeed Agilee*Assistant Examiner* — David Truong(74) *Attorney, Agent, or Firm* — Wolf, Greenfield & Sacks, P.C.(57) **CLAIM**

The ornamental design for an inflatable towable raft, as shown and described.

DESCRIPTION

FIG. 1 is a perspective view of an inflatable towable raft in accordance with our design.

FIG. 2. is an elevations view of the front side of the inflatable towable raft of FIG. 1.

FIG. 3 is an elevational view of the back side of the inflatable towable raft.

FIG. 4 is a top plan view of the inflatable towable raft.

FIG. 5 is a bottom plan view of the inflatable towable raft.

FIG. 6 is an elevational view from the left end of the inflatable towable raft of FIG. 1; and,

FIG. 7. is an elevational view of the right end of the inflatable towable raft of FIG. 1.

The broken lines in the drawings depict portions of the inflatable towable raft that form no part of the claimed design.

1 Claim, 6 Drawing Sheets
